METHOD AND APPARATUS FOR PRODUCING SOUND WAVES

Application filed December 17, 1931. Serial No. 581,555.

This invention relates to new and useful improvements in a method and apparatus for producing sound waves.

The primary object of this invention is to provide a new method of producing sound waves, and apparatus for carrying out this method.

A further important object of the invention is to provide means for producing sound waves of super-volume which is especially adapted for use in public address systems, although not limited to this type of use.

A further object of the invention is to provide means for producing sound waves, which means is capable of use as a loud speaker in connection with radio receiving sets. In this particular use, the device is adapted to relieve the delicate voice currents of the work of moving large members, such as cones or diaphragms, as well as large volumes of air to form sound waves, as is required in most present day loud speaker units.

A further object of the invention is to provide a device which is capable of increasing the efficiency of loud speaker units.

Still another object of the invention is to provide a device capable of taking full advantage of the push-pull operation of vacuum tube amplifiers.

Still another object of the invention is to provide a device capable of producing sound waves of a volume limited entirely by the capacity of the device to mechanically produce sources of fluid maintained at pressures above and below atmospheric pressure.

Another object of the invention is to provide a device capable of producing sound waves of any desired volume having very low frequencies.

Other objects and advantages of the invention will become apparent during the course of the following description.

In the accompanying drawings forming a part of this specification, and in which like numerals are employed to designate like parts throughout the same:

Figure 1 is a top plan view of the device embodying this invention,

Figure 2 is a front elevational view of the device illustrated in Fig. 1,

Figure 3 is a fragmentary vertical sectional view taken on line 3—3 of Fig. 1,

Figure 4 is a fragmentary horizontal sectional view taken on line 4—4 of Fig. 3,

Figure 5 is a vertical sectional view taken on line 5—5 of Fig. 3,

Figure 6 is a vertical sectional view taken on line 6—6 of Fig. 3,

Figure 7 is a vertical sectional view taken on line 7—7 of Fig. 3, and

Figures 8 and 9 represent two sines of simple air waves which have been shaded to compare the relative expenditures of energy in two different types of sound wave producing devices.

Briefly described, this invention consists of apparatus capable of mechanically producing a push-pull movement of the air column in a horn or other similar sound distributing device with the mechanically produced push-pull action controlled electrically. The device consists of a source of fluid maintained at a pressure above atmospheric pressure, and confined within the pressure reservoir A and the pressure working cylinder B and a source of fluid maintained at a pressure below atmospheric pressure and confined within a pressure reservoir C and a working cylinder D. These sources of fluid maintained under pressure and vacuum are controlled by a valve unit E which establishes and destroys connection between these two sources and a horn or the like, F. The movable element of the valve unit E is actuated in this particular illustration of the invention, by a "Dynamic" voice coil unit G.

The independent source of pressure and vacuum are alternately connected with the horn F, at an audio frequency, in proportion to the variations in amplitude and frequency of a controlling electrical current, such as a voice current.

For the purpose of enabling those skilled in the art to arrive at a complete understanding of the features of the construction, the device will now be described in detail.

A suitable base or supporting surface 10 is provided, and has suitably secured thereto a mounting plate 11. Positioned upon one end portion of the plate 11 is a cylinder 12

80

85

90

95

100

which is closed at its lower end by the plate 11, and is provided with a closure plate or head 13 at its upper end. The cylinder 12, head 13, and plate 11, are tied together by 5 means of a plurality of rods 14, which pass through the head 13, and are threaded at their lower ends into suitable apertures formed in the plate 11. This structure constitutes the pressure reservoir A in which 10 fluid, such as air, is stored under a pressure above atmospheric pressure. This fluid is stored in this reservoir for the purpose of maintaining the same at a uniform pressure, and is supplied thereto from a pressure pump, or the like, not shown, through the conduit 15. The fluid under pressure confined within the reservoir A is conveyed to the pressure working cylinder B by means of a conduit 16. 20 The opposite end portion of the plate 11 has positioned thereupon a second cylinder 17, which is closed at its lower end by the plate 11 and at its upper end by the plate 18. Tie rods 19 are employed to connect these 25 various elements which cooperate with each other to form the reservoir C which constitutes a source of fluid maintained under pressure below atmospheric pressure, or maintained at a vacuum. This vacuum reservoir 30 C is connected to a suitable vacuum pump, not shown, by means of a conduit 19', and is connected to a vacuum working cylinder D by means of a conduit 20. The outer end of the pressure working cylinder B is supported by means of an end plate 21 connected to a mounting block 22 which 35 is in turn secured to the end plate or head 13 of the pressure reservoir A. The outer end of the vacuum working cylinder D is secured to the head 18 of the vacuum reservoir C by means of an end plate 23 secured to a supporting block 24, which in turn is connected to the head 18. These working cylinders B and D are arranged substantially 40 in axial alignment with respect to each other, and have their inner ends connected respectively to end plates 25 and 26 by means of tie rods 27 and 28. These tie rods pass through the end plates 21 and 23, and are threaded 45 at their inner ends into apertures formed in the plates 25 and 26. These plates 25 and 26 are relatively adjustably tied together by screws 29, which are associated with the various corners of the said plates. For the purpose 50 of maintaining these plates 25 and 26 in proper spaced relation with respect to each other, the plate 25 has formed therein four elongated apertures 30, capable of receiving pins 31 projecting from the spacing blocks 32. These spacing blocks are secured to the plate 26 by means of screws 33. Adjusting 55 screws 34 are associated with the elongated apertures 30 and project into the same in the directions of their major dimensions. It 60 will be seen that by loosening the various

screws 29 and adjusting the various screws 34, the two plates 25 and 26 may be shifted relative to each other in parallel vertical planes.

For the purpose of sealing the space between the two plates 25 and 26, and yet permit relative adjustment between the same, these plates have secured to their inner faces channeled strips 35. A strip or strips 36 of flexible material, such as cork, are positioned with their opposite edges seated in the channels of the members 35. The strip or strips 36 terminate at relatively spaced ends 37 to form a lateral opening between the plates 25 and 26. This opening registers with the bore of a horn or the like, 38. It will be seen that the space between the plates 25 and 26 forms a sound chamber 39 which communicates with the horn 38.

This sound chamber 39 also acts as a valve chamber for housing the valve 40. This valve is formed of two parallel plates 41 and 42. These plates are held in spaced relation with respect to each other by spacing blocks 43 at the opposite ends thereof, which leave the sides open. Communication, therefore, is established between the interior 44 of the valve unit and the sound chamber 39. Each valve plate 41 or 42 is provided with a plurality of transversely extending elongated slots 45 and the slots in the respective valve plates are arranged in transverse alignment.

This valve unit 41 is adapted for movement within the sound chamber 39 and is intended to partake of slight oscillatory movement in a vertical direction.

For the purpose of supporting this unit 41 to permit of this movement, a pair of parallel spring members 46 are connected at their inner ends to the spacing blocks 43, and are connected at their outer ends to a support 47 which is suitably positioned between and secured to one of the plates 25 and 26.

The said plates 25 and 26 are each formed with a plurality of slots 48, and the slots of the respective plates are arranged in staggered relation with respect to each other. That is to say, the slots 48 of the plate 25 are out of transverse alignment with the slots 48 of the plate 26. The slots 45, formed in the valve unit 40, and the slots 48 formed in the end plates 25 and 26, are of equal size, with the result that when the valve unit 40 is positioned with the slots 45 in the plate 41 registering with the slots 48 in the end plate 25, communication will be established between the pressure working cylinder B and the sound chamber 39. Likewise, when the slots 45 in the valve plate 42 register with the slots 48 in the end plate 26, the vacuum working cylinder D will be in communication with the sound chamber 39. It will be noted, however, that due to the staggered relation of the slots 48 in the respective plates 25 and 26, both of the working cylinders B and

D can never be connected at one time to the sound chamber 39.

For the purpose of balancing the valve unit 40 against the combined actions of the fluid maintained under pressure and vacuum on opposite sides of the same, the valve blocks 43 have connected thereto a pair of parallel spring blades 49. These blades extend through openings 50 formed in the end plate 25 and extend into the bores 51 of the guide housings 52. Positioned within each housing is a sliding block 53, and the inner ends of the spring members 49 are connected to these blocks. Each block is formed with an internally threaded aperture 54 which receives a threaded end 55 of an adjusting rod 56. These guide housings 52 are open at their inner ends and have the various edges of these inner ends secured by brazing, welding, or the like, to the face of the plate 26. It is to be understood that any other suitable form of connection may be provided between these housings 52 and the end plate 26, and that if necessary, packing material may be located between the housings and the end plate.

The outer ends of the adjusting rods 56 pass through the end plate 21 and the end wall 57 of the pressure working cylinder B. The extremities of these rods are provided with screw-driver slots 58 by means of which the rods may be rotated. Washers, or other suitable stop elements 59 and 60 are connected to the rods 56 to prevent axial movement of the same in either direction.

The valve unit 40 must be permitted to freely move with respect to the end plates 25 and without binding or frictionally engaging the same. For this purpose, the spacing blocks 32, employed for maintaining the plates 25 and 26 in proper spaced relation with respect to each other, are machined to hold the plates 25 and 26 sufficiently spaced to enable the valve unit to slide relative to the same. The spacing between the valve unit and the respective end plates 25 and 26, as illustrated in Figs. 3 and 4, is exaggerated to better enable the features of construction of the valve unit to be clearly illustrated. It is to be understood that the valve plates 41 and 42 of the valve unit are positioned sufficiently close to the inner faces of the end plates 25 and 26 to prevent leakage between these opposing surfaces. It will be noted that the end plates 25 and 26 really function as valve seats for the respective valve plates 41 and 42. By adjusting the rods 56, the valve unit may be shifted transversely with respect to the valve seats or plates 25 and 26 for properly positioning the valve unit with respect to the valve seats. The spring connections 49, between the valve unit and the adjustable blocks 53, also function to balance or counteract the actions of the two different sources of fluid upon the valve unit.

For the purpose of actuating the valve in

timed relation with variations in amplitude and frequency of a controlling current, the valve unit is connected to a rod 61 through the medium of a flexible blade-like portion 62. This rod 61 is connected to the movable coil 63 of the "Dynamic" voice coil unit G. It is not intended to specifically describe the detailed features of construction of this unit G, as any suitable "Dynamic" unit may be employed. It is further to be understood that other suitable means may be utilized for causing desired reciprocation of the valve unit 40. In connection with the "Dynamic" unit 26, it is sufficient to say that the voice coil 63 is connected by the conical element 64 and the rods 65 to the valve rod 61, and that the movable coil 63 is supported by a flexible membrane 66, which in turn is mounted upon the outer pole piece 67 of the "Dynamic" unit G. This unit also includes an inner pole piece 68 and a coil 69. It is to be understood that the movable voice coil 63 is suitably connected to an amplifying unit or a radio receiving unit, and that the coil 69 is suitably connected to an external source of electricity, as is customary with dynamic units of this general type. The unit G is suitably supported upon the base plate 11 by means of legs or blocks 70, and is tied to this base plate by means of the rods 71 connected to the housing of the coil 69 by means of blocks 72.

The mode of operation of this device may be described as follows:

The pressure reservoir A and the vacuum reservoir C are to be connected to suitable sources of pressure and vacuum by means of the conduits 15 and 19'. The working cylinders B and D respectively are constantly in communication with the reservoirs A and C, and fluid will be maintained in these working cylinders B and D under pressure and vacuum respectively.

When the voice coil 63 is caused to move due to the ordinary operation of an amplifying unit or radio receiving set connected to the same, the valve unit 40 is caused to reciprocate within the sound chamber 39 for alternately establishing communication between the pressure working cylinder B and the sound chamber 39 and the vacuum working cylinder D and said sound chamber. When the pressure working cylinder B is placed in communication with the sound chamber 39, the air column in the horn 38 is pushed outwardly of the horn. When the vacuum working cylinder D is placed in communication with the sound chamber 39, the air column in the horn 38 is pulled inwardly. This alternate establishing of connections between the horn 38 and the cylinders B and D, produces the desired push-pull action within the horn 38 or causes the air column in the horn to move outwardly and inwardly to produce sound waves. It will be noted

that the force of this push-pull action upon the air column in the horn is dependent solely upon the degrees of pressure and vacuum maintained in the cylinders A and C, and that the volume of sound produced by this device, therefore, is substantially unlimited.

I am aware of the fact that sound wave producing devices have been designed which employ either pressure or vacuum. To the best of my knowledge and belief, my device is the first one to use both pressure and vacuum. When the pressure or vacuum alone is used, there is a material waste of energy. With my device, there is no waste, as energy is only being expended when the device is being modulated. Figure 8 illustrates a simple sine wave of a sound which has been shaded to represent the expenditure of energy and the absence of waste with my particular device. Figure 9 represents a simple sine wave of a sound shaded to represent the expenditure of energy to produce the sound and the loss of energy in the prior art type of device.

Referring to Fig. 8, it will be seen that a sound wave must start from some neutral point, which, in this case, is represented by the line X. The pressure part of the wave originates at O on line X, increases in amplitude until it reaches the point C, where it begins to fall off until it reaches the neutral line X at the point E. At this point, the wave begins to enter the vacuum region and continues down to the point D, which in a pure sound wave, will be as far below the line as point C is above the line. In my device, this condition is exactly duplicated, because at the instant an impulse is communicated to the valve, all ports are closed, and no energy is being consumed, this representing the neutral line X. As the valve unit 40 begins to open, because of this impulse, pressure will be released through the valve and will cause a rise in pressure in the horn. This pressure will continue to rise as the valve continues to open, until it reaches the point as at C, when the valve will begin to close and cause the pressure to drop until the valve reaches its centralized or normal position. The pressure will then be represented by the neutral or zero line at the point E. As the valve is following the wave form of the current which is moving it, it will continue past the neutral line X, and vacuum will be released causing a drop of pressure or a vacuum in the horn. The valve will continue to open and cause the pressure to continue to drop until point D is reached, when it again begins to close to the vacuum and allow the pressure to again reach the neutral or zero line X.

It will be seen from the above that when my device is not being excited or modulated, the valve ports will be closed to both vacuum

and pressure; therefore no expenditure of energy occurs. It will further be noted that there will actually be created pressure and vacuum in the horn, and that each reversal of the valve there will be a like reversal through the horn, the wave form resulting from this action will exactly coincide with the wave form which causes the valve to move.

In devices using pressure or vacuum alone, an entirely different condition exists as to wave form and as to efficiency. In referring to Figure 9, it will be seen that in such a device, the wave form must start at some point above or below the neutral or zero line, as at O, which at once discloses the fact that in using either pressure or vacuum alone, the valve, when in its neutral position, must be open, and allow escape of energy. It must be open to such an extent that when handling sounds of its greatest amplitude, it will never entirely close or cross the neutral line. If this does occur, it is evident there will be a flat place on the wave as at line Z, Y, which means distortion. It will also be seen that in using one of these prior art devices, there must be a constant waste of energy. Any attempt to increase its volume will result in a greater waste of energy.

The shaded portions of Figs. 8 and 9 represent expended energy.

The line M in Fig. 8 is intended to represent the consumption of energy in my device, or the absence of consumption of energy, when the valve is centralized or when the device is not being modulated. The shaded space designated by the character N in Fig. 9 is intended to represent the consumption of energy in a device of the prior art, or a device using either vacuum or pressure alone when such a device is not being modulated. The air column in a horn associated with a device using either pressure or vacuum alone will always be moving in the same direction, and will never be completely stopped and never reversed. A sound wave thus created will not have the same form as the wave existing in the current controlling the valve, and, therefore, there will not be an exact duplication of this controlling wave.

It will be evident from a study of the sines shown in Figs. 8 and 9, that a device using either pressure or vacuum alone will consume the same amount of energy when not being modulated or excited as when it is being modulated to its full capacity. In my device, the input energy is in direct proportion to the output energy, and no loss occurs when the device is not being modulated or excited.

It is to be understood that the form of this invention herewith shown and described is to be taken as a preferred example of the same, and that various changes in the shape, size and arrangement of parts may be resorted to without departing from the spirit of the

invention or the scope of the subjoined claims.

Having thus described the invention, I claim:

5 1. In a device for producing sound waves, a sound chamber, a source of pressure, a source of vacuum, and means for successively connecting said separate sources with said chamber.

10 2. In a device for producing sound waves, a sound chamber, a source of pressure, a source of vacuum, means for controlling communication between said separate sources and said chamber, and means for actuating said 15 first mentioned means.

3. In a device for producing sound waves, a sound chamber, a source of pressure, a source of vacuum, a valve for controlling communication between said separate sources 20 and said sound chamber, and means for actuating said first mentioned means.

4. In a device for producing sound waves, a sound chamber, a source of pressure, a source of vacuum, a valve for controlling communication between said separate sources and said sound chamber, and electro-magnetic means for actuating said first mentioned means.

5. In a device for producing sound waves, 30 a sound chamber, a source of pressure, a source of vacuum, a valve for successively connecting said separate sources with said chamber, and electro-magnetic means for actuating said valve.

35 6. In a device for producing sound waves, a sound chamber, and fluid means for causing movement of the air in said chamber in opposite directions at audible frequencies.

7. In a device for producing sound waves, a 40 chamber normally containing a column of air at atmospheric pressure, a source of fluid maintained at a pressure above atmospheric pressure, a second source of fluid maintained at a pressure below atmospheric pressure, and means for causing the said column of air to be subjected to the separate actions of the fluids in said two sources.

8. In a device for producing sound waves, a 50 chamber normally containing a column of air at atmospheric pressure, a source of fluid maintained at a pressure above atmospheric pressure, a second source of fluid maintained at a pressure below atmospheric pressure, means for causing the said column of air to be subjected to the separate actions of the fluids in said two sources, and means for rendering the actions of the first mentioned means responsive to variations in amplitude 55 and frequency of a controlling voice current.

9. A method of producing sound waves 60 comprising maintaining a body of fluid at a pressure above atmospheric pressure, maintaining a second body of fluid at a pressure below atmospheric pressure, and subjecting

an air column alternately to the separate action of said bodies of fluid.

10. A method for producing sound waves comprising maintaining a body of fluid at a pressure above atmospheric pressure, maintaining a second body of fluid at a pressure below atmospheric pressure, and connecting at an audio frequency an air column alternately to the separate actions of said bodies of fluid.

11. A method for producing sound waves comprising maintaining a body of fluid at a pressure above atmospheric pressure, maintaining a second body of fluid at a pressure below atmospheric pressure, and subjecting the air column alternately and to a variable extent to the separate actions of said bodies of fluid.

12. A method for producing sound waves comprising maintaining a body of fluid at a pressure above atmospheric pressure, maintaining a second body of fluid at a pressure below atmospheric pressure, and subjecting an air column alternately to the separate actions of said bodies of fluid in proportion to the variations in amplitude and frequency of a controlling voice current.

13. A device for producing sound waves comprising a pair of substantially aligned cylinders, means for maintaining fluid under pressure in one of said cylinders, means for maintaining fluid under vacuum in the second of said cylinders, a horn, and means for alternately connecting the said cylinders with the interior of said horn.

14. A device for producing sound waves comprising a pair of cylinders arranged in end to end relation, a valve chamber located between said cylinders, said cylinders having openings establishing communication between the same and said valve chamber, means for maintaining fluid under different degrees of pressure in said cylinders, a valve in the valve chamber, and means for actuating the valve to independently open and close the openings in said cylinders.

15. A device for producing sound waves comprising a pair of cylinders arranged in end to end relation, means for maintaining fluid under uniform pressure above atmospheric pressure in one of said cylinders, means for maintaining a fluid under uniform pressure below atmospheric pressure in the second of said cylinders, a valve chamber communicating with both of said cylinders, a valve for controlling the communication between said valve chamber and said cylinders, and means for actuating said valve in response to variations in amplitude and frequency of a controlling voice current.

16. In a device for producing sound waves, a sound chamber, fluid means for causing movement of the air in said chamber in opposite directions, and means for valving the action of the fluid means.

17. In a device for producing sound waves, a sound chamber, fluid means for causing movement of the air in said chamber in opposite directions, means for producing a magnetic field, and means under the influence of the last mentioned means for controlling the fluid means.
18. In a device for producing sound waves, a sound chamber, fluid means for causing movement of the air in said chamber in opposite directions, means for producing a constant magnetic field, means for varying the constant magnetic field, and means influenced by the resultant varying field for controlling the action of the fluid means.
19. In a device for producing sound waves, a sound chamber, fluid means for causing movement of the air in said chamber in opposite directions, means for producing a constant magnetic field, means for varying the constant magnetic field, and means influenced by the resultant varying field for modulating the moving air in said chamber in accordance with the varying resultant field.
20. In a device for producing sound waves which employs compressed and rarified air as the sound wave producing medium, means for producing a varying magnetic field, and means influenced by said field for controlling the action of said compressed and rarified air.
21. In a device for producing sound waves which employs compressed and rarified air as the sound wave producing medium, means for valving said air, and electromagnetic means for operating the valving means in accordance with telephonic currents supplied to the electro-magnetic means.
22. In a device for producing sound waves which employs compressed and rarified air as the sound wave producing medium, a valve having stationary and movable parts for controlling the action of said air, and electromagnetic means operated by telephonic currents for controlling the movable part of said valve.
23. In a method of producing sound waves comprising creating a body of compressed air, creating a body of rarified air, producing a varying magnetic field, and causing movement of a column of air by subjecting the same to the actions of said bodies of air in accordance with the variations of said field.
24. In a device for producing sound waves, a sound chamber, a source of pressure, a source of vacuum, and means for connecting said separate sources with said chamber.
25. In a device for producing sound waves, a column of air, a source of compressed air, a source of rarefied air, and means for employing said compressed and rarefied air for causing movement of the column of air.
26. In a device for producing sound waves, a sound chamber, a source of pressure, a source of vacuum, and valve means for controlling communication between said separate sources and said chamber.
27. In a device for producing sound waves, a sound chamber, a source of pressure, a source of vacuum, means for controlling communication between said separate sources and said sound chamber, and electrical means for actuating said first mentioned means.
28. A method of producing sound waves comprising maintaining a body of fluid at a pressure above atmospheric pressure, maintaining a second body of fluid at a pressure below atmospheric pressure, and subjecting an air column to the action of said bodies of fluid.
29. A method of producing sound waves comprising maintaining a body of fluid at a pressure above atmospheric pressure, maintaining a second body of fluid at a pressure below atmospheric pressure, and subjecting at an audio-frequency an air column to the actions of said bodies of fluid.
30. A method for producing sound waves comprising maintaining a body of fluid at a pressure above atmospheric pressure, maintaining a second body of fluid at a pressure below atmospheric pressure, and subjecting an air column to a variable extent to the actions of said bodies of fluid.
31. A method for producing sound waves comprising maintaining a body of fluid at a pressure above atmospheric pressure, maintaining a second body of fluid at a pressure below atmospheric pressure, and subjecting an air column to the actions of said bodies of fluid in proportion to the variations in amplitude and frequency of a controlling voice current.
32. In a device for producing sound waves, a column of air, fluid means for causing movement of the air in said column in opposite directions, and means for modulating the moving air.
33. In a device for producing sound waves, a column of air, a valve, two separate sources of air maintained at different pressures and adapted, under the control of said valve, to cause movement of the air column to produce sound waves, means for balancing the valve against the actions of said sources of air, and means for controlling said valve.
34. In a device for producing sound waves, a column of air, a slidably movable valve, two oppositely positioned sources of air maintained at different pressures and adapted, under the control of said valve, to cause movement of the air column to produce sound waves, means supporting and balancing the valve against the actions of said sources of air, and means for controlling said valve.
35. In a device for producing sound waves, a column of air, a source of compressed air, a source of rarefied air, and means for controlling communication between said column and said chamber.

and sources so that the column can be affected by one source only at any one time.

36. A method of producing sound waves comprising subjecting a body of air to the 5 independent actions of different air pressures capable of moving said air column in different directions, and modulating the moving air.

In testimony whereof I affix my signature.
